fig. 2

FIG. 1 is a front perspective view of a combined flag and holder therefor showing my new design; and

FIG. 2 is a rear perspective view.

This is a continuation-in-part of my earlier design patent application, Ser. No. D. 25,961, filed Sept. 13, 1970, and now abandoned.

I claim:

The ornamental design for a combined flag and holder therefor, as shown.
